Primary Examiner — Susan Moon Lee

(57) **CLAIM**

The ornamental design for an elevated pet bowl, substantially as shown and described.

DESCRIPTION

FIG. 1 is a top perspective view of an elevated pet bowl showing my new design;

FIG. 2 is a bottom perspective view thereof;

FIG. 3 is a front elevational view thereof;

FIG. 4 is a rear elevational view thereof;

FIG. 5 is a side elevational view of the elevated pet bowl, the opposite side being a mirror image thereof;

FIG. 6 is a top plan view thereof;

FIG. 7 is a bottom plan view thereof; and,

FIG. 8 is a top and front perspective view showing two elevated pet bowls according to my new design in a stacked arrangement.

1 Claim, 4 Drawing Sheets(56)
